UNITED STATES PATENT OFFICE.

OTTO KERSTEN, OF DETROIT, MICHIGAN.

COMMUTATOR.

1,340,857.

Specification of Letters Patent. Patented May 18, 1920.

Application filed November 25, 1916. Serial No. 264,002.

To all whom it may concern:

Be it known that I, OTTO KERSTEN, a citizen of the United States of America, residing at Detroit, in the county of Wayne and 5 State of Michigan, have invented certain new and useful Improvements in Commutators, of which the following is a specification, reference being had therein to the accompanying drawings.

10 My invention aims to provide a commutator or timer for the ignition system of an internal combustion engine, particularly an engine having four spark plugs and coil units and a magneto or batteries associated there- 15 with, so that the commutator may determine the instant at which the spark plugs must fire the explosive mixture in the cylinders of the engine. To this end I have devised a commutator or timer wherein the primary circuit of an ignition system is interrupted or 20 the "make and break" of the circuit accomplished through the medium of novel contacts movable to and from the stationary contacts, in contradistinction to those contacts which ordinarily have a rolling or wiping action relative to each other.

25 My invention further aims to provide a commutator which will insure a smooth running engine and facilitate the starting of the same, and the mechanical construction contributing to these results will be herein- 30 after described and then claimed.

Reference will now be had to the drawing, wherein—

35 Figure 1 is a diagrammatic view of the ignition system of an internal combustion engine; showing the commutator in end elevation or at a right angle to the natural position on the engine;

40 Fig. 2 is a rear elevation of the commutator, and

Fig. 3 is a longitudinal sectional view of the same.

45 In the drawing, the reference numeral 1 denotes a conventional form of internal combustion engine having spark plugs 2 serving the cylinders of the engine, said spark plugs being electrically connected, as at 3, to coil units or a box 4 which has the 50 terminals thereof electrically connected, as at 5, to the binding post 6 of a commutator casing 7. The coil units or box 4 is also electrically connected as at 8, to a magneto or battery (not shown). This is the ordinary and well known ignition system where- 55 in a primary circuit is adapted to be main-

tained by utilizing metallic parts and interrupting the circuit at the commutator, which is suitably secured to the engine and is operated through the medium of a cam 60 shaft 9 extending into the commutator casing 7.

The binding posts 6 are suitably insulated from the casing 7 and the inner ends of said binding posts have tungsten points 10. Ad- 65 jacent the inner ends of the binding posts 6 are studs or posts 11 suitably connected to the casing 7 and provided with pivoted clevises or yokes 12. The clevises 12 have small apertured ears 13 at one end thereof 70 and large apertured ears 14 at the opposite end thereof, the small apertured ears 13 being pivotally mounted on these studs 11 with a coiled spring 15 encircling each stud between the small ears 13 pivoted thereon. 75 The springs 15 have end convolutions there- of engaging the inner wall of the commuta- 80 tor casing 7, and other end convolutions en- gaging in the clevises 12, said springs being constantly under tension so as to shift the 85 clevises when the free ends thereof are re- leased.

Journalized in the free ends of the clevises between the large ears 14 are rollers 16, pref- 85 erably made of fiber or any material. These 90 rollers are adapted to normally engage a roll or head 17 fixed on the end of the shaft 9 within the commutator casing 7, said roll or head having a flat or inset surface 18 which permits the clevises 12 to fully shift 95 without contact with the roll 17 due to the tension of the spring 15.

The clevises 12, intermediate the ends 95 thereof have arms 19 provided with tung- 100 sten points 20, and these tungsten points are 105 constantly opposite the tungsten points 10 of the binding posts 6 so as to contact there- with when permitted to do so by the roll or head 17 presenting its flat or inset surface or facet to one of the rollers 14. With one 100 of the rollers out of contact with the roll, the full tension of the spring associated with the roller causes a positive engagement of the tungsten points and there is no dan- 110 ger of the circuit being through the wall. 105

As will be understood, the structure dis- closed embodies a rotating control element, and means for supporting the movable contact of a pair of opposing contacts, with the means formed of an element—the 110 clevis—pivoted at one end and having its opposite end formed with a face which is

normally maintained in contact with the control element by spring 15, the element carrying a member supporting the movable contact, this member projecting outwardly 5 from the element from a point the plane of which intersects a plane connecting the pivot point and the face at right angles, the member being shown as in the form of an arm, the arm being so arranged as to 10 normally extend on a plane approximating a right angle with the axis of the terminal contact, thus causing the arm and element to combinedly produce a structure having a general configuration approaching a 15 Y-shape in elevation. As a result it is possible to locate the pivot point of the element a maximum distance from the control element, and yet place it in proximity to the terminal contact so as to provide a compact 20 structure and yet at a sufficient distance from the stationary contact as to prevent liability of electrical difficulties. By this arrangement sufficient space is provided, between adjacent terminal contacts, 25 within which the follower—the roller in the embodiment shown—can have its movement without tending to provide interference in operation. And while these advantages are present, the entire structure can 30 be produced with a casing of comparatively small size even where the number of stationary contacts is such as to locate them in spaced relation with an angular spacing distance of 90°, without crowding the interior of the casing or bringing the zone of 35 operation of one of such lever units into that of another unit or within the quadrant defined by adjacent stationary contacts and the shaft axis, excepting such as 40 might be provided by carrying the element member beyond such quadrant in supporting its contact in opposition to its coöperating stationary contact; at the same time it permits a symmetrical arrangement, in that 45 each unit has the same relation with the terminal with which it coöperates as every other unit. In other words, the structure is such as to permit the formation of a compact whole in which electrical interference 50 is avoided, the movement of each unit is unaffected by that of any other, and yet provide for a maximum number of terminals, and the use of a control element of minimum diameter. In addition, the arrangement is such as to permit the use of 55 a comparatively large roller as the member in contact with the control element, a positive advantage under the conditions of speed requirements in devices of this kind, 60 the diameter of roller permitted causing the R. P. M. ratio difference between the roller and the control element to be small as compared to prior structures, where a roller forms the follower of the control element, 65 the particular form of unit permitting free

movement of a roller of such size within the small space.

By reference to Fig. 2 of the drawing, it will be noted that three of the contacts are constantly broken or open while the fourth contact is made or closed. In consequence of this constructive arrangement, rotation of the roll or head 17 causes the contacts to be successively broken, and since the rollers 16 are made of fiber or other insulation material and the binding posts 6 thoroughly insulated relative to the commutator casing, the possibility of short circuits in connection with the commutator is reduced to a minimum. I attach considerable importance to the fact that the contacts do not wipe each other but are of positive make and break electrical connections, the making of the connections being automatic and the breaking mechanically performed. It is obvious that the number of contacts depends upon the number of cylinders in connection with the engine, and while there is illustrated a preferred embodiment of my invention, it is to be understood that the structural elements are susceptible to such variations and modifications as fall within the scope of the appended claims.

What I claim is:—

1. In a distributing commutator having a plurality of terminal contacts spaced substantially in a circular series substantially concentric with the axis of rotation of a shaft, and wherein the opposing coöperating contacts are movable toward and from such stationary contacts, a control structure carried by and movable with the shaft, and means for supporting said movable contacts individually, said means including a contact-carrying member, a pivoted element having a face at its free end adapted to contact with the control structure, said member being permanently positioned relative to the element and projecting from such element on a plane intersecting a plane connecting the pivot point and said face with the point of intersection of the planes located between and spaced from both axis and face of the element, said element and said member combinedly producing an approximately Y-shape configuration in elevation, said control structure having a face operative in the oscillation of said elements successively, and means whereby the element face is caused to normally maintain contact with the control structure.

2. In a distributing commutator having a plurality of terminal contacts substantially uniformly spaced in a circular series substantially concentric with the axis of rotation of a shaft, and wherein the opposing coöperating contacts are movable toward and from such terminal contacts, a control element carried by and movable with the shaft, and means for supporting said mov-

- able contacts individually, said means including a unit having a configuration in elevation approaching that of Y-shape and having a pivotal axis and a face normally maintained in contact with the control element, the unit contact support being positioned approximately on a plane intersecting a plane connecting the unit axis and said face at right angles with the point of intersection between and spaced from both axis and face, each unit having the same positional relation with its terminal contact and the shaft as an adjacent unit, whereby a symmetrical arrangement of units is provided within the commutator casing.
3. A commutator as in claim 2 characterized in that the pivot axis of each unit is positioned outside of a line corresponding to a circle the radius of which corresponds to the distance between a terminal contact and the shaft axis.
4. In a distributing commutator having a plurality of terminal contacts substantially uniformly spaced in a circular series substantially concentric with the axis of rotation of a shaft, and wherein the opposing coöperating contacts are movable toward and from such terminal contacts, a control element carried by and movable with the shaft, and means for supporting said movable contacts individually, said means including contact-carrying pivoted units, corresponding in number to the number of terminal units, each unit including a sheet-metal clevis having opposed apertured ears at one end to receive the unit pivot and having its opposite end formed to normally bear on the control element, an arm projecting from the clevis in a manner to produce therewith a general configuration in elevation approaching Y-shape, said arm carrying the movable contact, a pin forming the unit pivot, and a spring on said pin and coöperative with the unit and casing to normally maintain contact of unit and the control element.
5. A commutator as in claim 4 characterized in that the clevis free end is in the form of apertured ears between which is located a roller normally bearing on the control element.
- In testimony whereof I affix my signature in the presence of two witnesses.
